MERV Filter Rating

Copy Link Close

The MERV system is an industry standard that rates air filters on a scale from 1 to 16 based on how well they remove particles in three size ranges. A higher rating means a filter removes more particles.

Removes fewer particles

Prefilter

Protect HVAC equipment and extend the life of other higher-efficiency filters. Prefilters capture large particles such as sanding dust, textile fibers, and rock spores.

MERV 4

Unfiltered Air Filter

Filtered Air

MERV 4 filters remove fewer than 20% of large particles (3 to 10 microns), such as mold spores and cement dust.
